UNITED STATES PATENT OFFICE

2,610,328

VENTILATED TOILET BOWL

Russell H. Miller, Hutchinson, Kans.

Application December 16, 1948, Serial No. 65,569

3 Claims. (Cl. 4—213)

1

This invention relates to ventilated toilet bowls, the primary object of the invention being to provide means for circulating air through the toilet bowl creating a suction therein, the means for creating suction being controlled by a weight on the bowl seat.

An important object of the invention is to provide an electric fan operated by a circuit controlled by the movements of the cover of the seat, to the end that the circuit to the motor will remain broken while the cover is in its closed position, even though a person is seated on the cover.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Figure 1 is a fragmental plan view of a closet bowl equipped with a seat and cover constructed in accordance with the invention.

Fig. 2 is a vertical sectional view through the rear end of the closet bowl and hinge support for the seat and cover.

Fig. 3 is an enlarged elevational view partly broken away illustrating the position of the mercury switch used in the circuit, when the cover is swung to its closed position.

Fig. 4 is a similar elevational view of the supporting hinge of the device illustrating the position of the mercury switch when the cover is in its open position.

Fig. 5 is a similar elevational view of the hinge structure illustrating the circuit as completed through the mercury switch when pressure is directed to the operating lever, the cover being open.

Fig. 6 is a sectional view taken on the line 6—6 of Fig. 3.

Referring to the drawings in detail, the reference character 5 indicates the conventional toilet bowl with which the attachment is used. The device forming the subject matter of the invention comprises the suction intake member which is in the form of a housing 6 formed with a reduced forward end 7, which is open to the space directly between the seat 8 and top or upper edge 9 of the bowl 5.

Communicating with one end of the intake member 6 is the pipe 10 that communicates with

2

the suction fan housing 11 in which the suction fan 12 operates, the suction fan housing being also in communication with a discharge pipe, not shown, through which air is directed. The rear end of the seat 8 is mounted upon hinge members pivoting on hinge pin 15 for vertical movement with respect to the bowl 5 and is held in its elevated position under normal conditions, by means of the coiled spring 13 which is shown as seated in a recess in the lower surface of the seat, the spring resting on the upper edge of the bowl. Pivotedly connected with the hinge member 16 at one side of the hinge, is the arm 17, which arm has pivotal connection with the arm 18, that in turn is secured to one end of the shaft 19, which shaft operates in a bearing opening formed in one end wall of the suction intake member 6. Mounted within the suction intake member 6 and secured to the inner end of the shaft 19, is the arm 20 on which the plate 21 is pivotally mounted, the plate 21 having the clip 22 mounted thereon, which clip grips the mercury switch 23 securing the switch in position. The mercury switch carries contacts in one end thereof, and these contacts connect with the wires 24 that in turn provide a circuit between the mercury switch and motor 25 of the fan 12. The position of the arm 20 with respect to the shaft 19 is such that when the arm 20 is moved, due to slight frictional contact between the plate and arm, the plate will swing upwardly to the position as shown by Fig. 4, when the cover 14 is moved upwardly to the dotted line position. The position of the plate 21 shown by Fig. 4, is the limit of the movement of this plate when operated by the cover and arm 17. When the mercury switch is in this position, the contact points of the mercury switch are free and the circuit through the wires 24 is broken.

The reference character 26 indicates an operating arm pivotally connected with the wall of the member 6, the end 27 of the arm 26 being rounded and disposed directly under the rear edge of the seat 8. The opposite end of the arm 26 connects with the switch actuating arm 28 which is constructed to fit over the shaft 19, as clearly shown by Fig. 4 of the drawings. It follows that when pressure is directed to the rear of the seat 8, the seat engaging the end 27 of the arm 26 will cause the opposite end of the arm to be elevated from the dotted line position, as shown by Fig. 5, whereupon the arm 28 moves upwardly engaging the plate 21 and tilting the plate and mercury switch 23 so that the mercury will move to bridge the contacts in one end thereof, completing the circuit to the motor 25.

When the weight of the person is removed from the seat 8, the seat 8 will move upwardly under the action of the spring 13, whereupon the arm 26 will return to the position shown by Fig. 4 of the drawings.

When the cover 14 is moved to the position to close the seat, the mercury switch will swing downwardly to the position shown by Fig. 3.

When the motor is in operation, a suction will be created around the seat between the seat and toilet bowl, the suction drawing off air through the pipe 10 and discharging the air to the atmosphere.

Having thus described the invention, what is claimed is:

1. The combination with the hinged seat cover of a toilet bowl, of a ventilating attachment comprising a suction intake housing having an open side communicating with the space between the seat and upper edge of the bowl, a suction pipe connected with the intake housing, a motor operated suction fan operating within the pipe adapted to draw gases from the bowl, a wiring system providing an electric circuit between the fan motor and source of electricity supply, a mercury switch in the wiring circuit mounted within the housing, a switch operating arm, an arm connecting the switch operating arm and cover, adapted to partially operate the switch upon movement of the cover to its open position, a pivoted arm extending into the housing, the outer end of the pivoted arm engaging the lower surface of said seat, an arm extending upwardly from the inner end of said pivoted arm and operated by downward movement of the seat, further operating said switch and completing the circuit to the fan motor.

2. The combination with the hinged seat and cover of a toilet bowl, of a ventilating attachment comprising a suction intake housing having an open side communicating with space between the seat and upper edge of the bowl, a suction pipe connected with the intake housing, a motor operated suction fan operating within the pipe

adapted to draw gases from the bowl, a wiring system providing an electric circuit between the fan motor and source of electricity supply, a mercury switch in the circuit pivotally mounted within the housing adapted to complete the circuit to the fan upon upward movement of the cover, an arm connected with the cover, means for transmitting movement of said seat cover through said arm, to said mercury switch partially tilting said switch, an operating arm extending into the housing with one end engaging the seat and a switch actuating arm mounted on the other end of the operating arm and engaging said switch and moving the switch to its limit to complete the circuit to the fan when pressure is directed to the seat and operating arm.

3. The combination with the hinged seat and cover of a toilet bowl, of a ventilating attachment comprising a suction intake housing having an open side communicating with the space between the seat and upper edge of the bowl, a suction pipe connected with the intake housing in communication therewith, a motor operated suction fan operating within the pipe and adapted to draw gases from the bowl, a wiring system providing an electric circuit between the fan motor and a source of electricity supply, a mercury switch in the circuit mounted in the housing, an operating arm operated by downward pressure on the toilet seat and connected to a switch actuating arm for raising said switch actuating arm, and means controlled by the movement of the cover of the seat to its open position for moving said switch into the path of travel of said switch actuating arm.
